US0D1052563S

(12) **United States Design Patent** (10) Patent No.: **US D1,052,563 S**
 (45) Date of Patent: ** Nov. 26, 2024

(54) **RFID INLAY**

- (71) Applicant: **CCL Label, Inc.**, Framingham, MA (US)
- (72) Inventors: **Henry Nguyen**, Holland, MI (US); **Michael Isabell**, East Grand Rapids, MI (US)
- (73) Assignee: **CCL Label, Inc.**, Framingham, MA (US)

(**) Term: **15 Years**(21) Appl. No.: **29/893,644**(22) Filed: **Jun. 1, 2023**(51) LOC (14) Cl. **14-03**
